Primary Examiner — Holly E Thurman*Assistant Examiner* — Dustin Andrew Griffith(74) *Attorney, Agent, or Firm* — Ying-Ting Chen; Law Office of Michael Chen(57) **CLAIM**

The ornamental design for a backpack, as shown and described.

DESCRIPTION

FIG. 1 is a perspective view of the backpack showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof; and

FIG. 7 is a top plan view thereof.

FIG. 8 is an enlarged view of portion 8 in FIG. 1;

FIG. 9 is an enlarged view of portion 9 in FIG. 1; and,

FIG. 10 is an enlarged view of portion 10 in FIG. 1.

The broken line is for the purpose of depicting the zipper portions of the backpack and forms no part of the claimed design.
